UNITED STATES PATENT OFFICE.

WILBER L. ORME, OF CAMBRIDGE, OHIO.

DESIGN FOR A SERVICE TRAY FOR RELISH OR THE LIKE.

Application filed January 31, 1927. Serial No. 20,557. Term of patent 7 years.

To all whom it may concern:

Be it known that I, WILBER L. ORME, a citizen of the United States, residing at Cambridge, in the county of Guernsey and State of Ohio, have invented a new, original, and ornamental Design for Service Tray for Relish or the Like, of which the following is a specification, reference being had to the accompanying drawing, forming part thereof.

Figure 1 is a top plan of a service tray for relish or the like, showing my new design;

I claim:

The ornamental design for a service tray for relish or the like, as shown.

WILBER L. ORME.
